G. W. DONLEY,
INWALL GARBAGE RECEIVER,
APPLICATION FILED SEPT. 11, 1916.

1,235,122.

Patented July 31, 1917.

UNITED STATES PATENT OFFICE.

GEORGE W. DONLEY, OF CLEVELAND, OHIO, ASSIGNOR TO THE DONLEY BROTHERS COMPANY, OF CLEVELAND, OHIO, A CORPORATION.

INWALL GARBAGE-RECEIVER.

1,235,122.

Specification of Letters Patent. Patented July 31, 1917.

Application filed September 11, 1916. Serial No. 119,372.

To all whom it may concern:

Be it known that I, GEORGE W. DONLEY, a citizen of the United States, and a resident of Cleveland, in the county of Cuyahoga and State of Ohio, have invented new and useful Improvements in Inwall Garbage-
receivers, of which the following is a specification.

This invention relates to garbage receptacle receivers, and particularly to means for supporting and giving access to a removable garbage pail normally confined closely in a recess in a wall.

Primarily, the object of my present invention is to provide simple and inexpensive means for hanging in a wall and shutting closely therein a garbage pail, and for giving easy and convenient access to said pail both for introducing garbage into it and for removing it. A further object is to accomplish this result by employing only two main elements of construction, a wall-frame and a door hung thereon, and providing them with simple automatic stops.

Minor objects will become apparent from the following description of a preferred embodiment of the invention, reference being had to the accompanying drawing in which—

Figure 1 is a sectional elevation of a receiver set in a wall.

Fig. 2 is a sectional plan view taken on line 2—2 of Fig. 1, the pail being removed.

Fig. 3 is a detailed side view, and

Fig. 4 is a front view showing one of the hinges.

Fig. 5 is a detailed section taken on line 5—5 of Fig. 2.

The reference letter *a* indicates a casting of angular cross-section, preferably of iron or steel, framed about a rectangular opening, and adapted to be securely set in a recess in a wall *w*, with its encompassing flange *b* bearing against the face of said wall. Projections, screws, or any suitable means may be employed for more firmly anchoring the frame *a* to the wall or partition *w*; and the chamber *r* in said wall may be a mere recess in it, or when the wall is comparatively thin, the chamber may extend

through it to the lath *l* and plaster *m* of its opposite side, as shown in Fig. 1. Should it be desired to install the apparatus in a very thin wall, or a railing structure, it is obvious that a box-like casing, preferably of sheet metal, as indicated by dotted lines *c* in

Fig. 2, may readily be secured to the inner flanges of the frame *a* and extended rearward to inclose the garbage receptacle.

The wall-frame *a* is provided with a pair of hinge-brackets *h*—*h* projecting forward, 60 one on each side of its lower face; and its upper face has a forwardly extended flange carrying on its under side a depending stop-lug *s*, as shown in Fig. 1.

A door *d*, bulging outwardly as shown, is 65 fitted to close the front of the recess *r*, being hinged at its bottom to the frame *a* by means of its trunnions *t*—*t* rotatably supported respectively in the sockets of the hinge-brackets *h*—*h*; so that it can be easily 70 lifted off and removed from its hinges when desired. The top and sides of the door *d* overlap and bear normally against the face of the frame *a*, but its bottom edge does not overlap the said frame; thus, when the 75 door is tilted outward by pulling its handle *e*, the bottom edge enters the aperture of the frame *a*, as shown in Fig. 1.

The pail-bracket *f* is a plate flanged upwardly about its outer edge, and secured by 80 bolts *g* to the upper part of the door *d*, so as to project inwardly at right angles therefrom; and diagonal strut members *i*, one on each side, are inserted and bolted at their ends to lugs on the bracket and 85 door, as shown, to serve as additional supports. A large circular aperture is formed in the bracket-plate *f*, being beveled or chamfered off about its upper edge, as at *j*. Thus a garbage pail *p* may be inserted 90 through the aperture in the plate *f*, and its beaded rim *h* supported on the beveled edge *j*, so that the pail is suspended from the bracket *f*, as in Fig. 1.

A gravity hook-latch *n* is loosely pivoted, 95 or hinged on a stud *o*, to the upper inside face of one of the upright members of the frame *a*; said latch being preferably a flat metal bar with a hook-shaped notch formed in its forwardly projecting portion, and the 100 hook-end beveled off underneath, as shown in Figs. 1 and 5. A stop *u* is provided on the frame *a* to limit the downward swing of the latch *n*.

Off-sets *v* are formed in the upright flange 105 on each side of the bracket-plate *f*, as shown in Fig. 2, and on the side adjacent to the latch *n* the off-set flange has its upper and inner face beveled as at *y*, Figs. 1, 2 and 5, to engage and raise the hook end of the 110

latch n ; so that the latter will ride over the off-set v and drop behind its vertical face. A stop-lug z should also be formed on the inner edge of the plate f to insure 5 positive engagement with the stop s on the frame a .

In the operation of the device, the weight 10 of the pail p and its supporting bracket keeps the door d normally closed, so that odors, insects and animals are effectually 15 barred. To dump garbage into the pail the door d is tilted open by pulling the handle e until the hook-latch n engages the off-set v ; and to remove the pail the hook-latch 20 is raised by hand to release it from the off-set, and the door tilted farther outward until the lug z contacts with the stop s , as indicated by dotted lines in Fig. 1. After 25 the pail is removed or replaced, the door d will close automatically, the beveled surface y tripping the latch n over the off-set v as the door swings inward. Thus it is not necessary to lift the door d off of its hinges, except for the purpose of cleaning out the recess r , or in case of emergency requiring 30 complete access to all parts of the apparatus.

I further point out and distinctly claim as my invention—

- 30 1. A receptacle receiver set in a cavity in a wall and consisting of a rectangular open frame fixed to said wall about the rim of said cavity, a door hinged at its base to tightly close the opening in said frame, a bracket on the inner side of said door adapted to suspend by engaging its rim a removable receptacle therefrom, and means for limiting the outward swing of said door.
- 35 2. An in-wall garbage receiver comprising a wall-frame about a rectangular opening, a tiltable door hinged to close the opening in said frame, and a plate bracketed out from the inner side of said door provided with an aperture adapted to receive

and engage a garbage pail so as to suspend 45 it therefrom.

3. An in-wall garbage receiver comprising a wall-frame about a rectangular opening, a tiltable door hinged to tightly close the opening in said frame, a bracket on the inside 50 of said door adapted to engage a projecting rim of and thereby support a removable receptacle, and stops on said wall-frame and bracket adapted to engage with each other respectively to limit the tilting 55 of said door.

4. An in-wall garbage receiver comprising a wall-frame about a rectangular opening, a tiltable door hinged to close the opening in said frame, a bracket on the inside 60 of said door to support a removable receptacle, a gravity latch mounted to oscillate through a limited arc on said wall-frame, and a ratch-tooth on said bracket positioned to coöperate with said latch to limit the 65 service opening of said door and to stop the door swinging outwardly but not inwardly.

5. An in-wall garbage receiver comprising a wall-frame having a rectangular opening therethrough, a tiltable door to 70 close the opening in said frame, trunnion and open-topped socket hinges between the bases of said door and frame, a bracket on the inside of said door to support a removable receptacle, stops on said frame and door 75 to limit the extreme opening of the latter, and gravity latch with coöperating ratch-tooth means for limiting the service opening of said door.

In testimony whereof I affix my signature 80 in the presence of two subscribing witnesses, at Cleveland, Ohio, this 8th day of September, 1916.

GEORGE W. DONLEY.
